UNITED STATES PATENT OFFICE.

WILLIAM BUTTERFIELD, OF CHICAGO, ILLINOIS, ASSIGNOR TO THE DEERING HARVESTER COMPANY, OF SAME PLACE.

BUTT-ADJUSTER FOR SELF-BINDING HARVESTERS.

SPECIFICATION forming part of Letters Patent No. 605,388, dated June 7, 1898.

Application filed June 21, 1897. Serial No. 641,731. (No model.)

To all whom it may concern:

Be it known that I, WILLIAM BUTTERFIELD, of Chicago, in the county of Cook and State of Illinois, have invented certain new and useful Improvements in Butt-Adjusters for Self-Binding Harvesters, of which the following is a full description, reference being had to the accompanying drawings, in which—

Figure 1 is a front elevation of as much of a self-binding harvester as is necessary to illustrate my invention. Fig. 2 is a plan view with the grain-cover indicated by a dotted line. Fig. 3 is a sectional elevation on the line 3 3 of Fig. 1.

15 The butt-adjusting mechanism is located along the front edge of the binder-table B, as usual, between the elevator C and the binder-frame D, and serves to hasten the butts of the grain down the table to their final position

20 thereon.

E is the grain-cover at the upper end of the elevator. The elevator has the usual canvases e and e'.

A is the adjuster-bracket, in which is journaled the adjuster crank-shaft a', preferably adapted to receive rotation from the lower elevator-roller by means of the bevel-gears e² and e³. At its upper end is formed a double crank a². In the said bracket is also prefer-

25 ably pivoted a radius-rod A'. Hung upon wrists on the double crank are butt-adjusting boards A³ and A⁴ by means of suitable arms a³ and a⁴. The lower ends of the boards are supported by radius-links a⁵ and a⁶, said links being pivoted upon the swinging end of the radius-rod A' and the boards being pivoted conveniently thereto by any suitable means, those shown being brackets riveted thereto. Conveniently to the radius-rod is

30 pivoted the usual adjuster-lever F, extending diagonally back to the top of the elevator within convenient reach of the driver and provided with the usual means for holding it in any given position of adjustment. The

35 double cranks are substantially on opposite sides of the shaft a', so that one of the boards is acting upon the grain aggressively when the other is making a return movement preparatory to a succeeding aggressive movement.

40 As is well known, in some conditions of grain there is a tendency for the upper ele-

vator-canvas to carry bunches of straw back between itself and the grain-cover and choke the elevator. Similarly the lower elevator-canvas sometimes carries straws down between itself and the upper edge of the binding-table. The upper board can be of such length as to approach very close to the upper elevator-roller and the space thereabove where the straws sometimes choke, so as to 55 positively take the grain away from the same without allowing it to be carried over. For that purpose its end nearest the roller is provided with an aggressive toothed slat a⁷. The lower board, hung upon the lower crank, 60 while having preferably the same throw as the upper one, can be proportioned differently, so as to take the grain from the lower elevator-roller before it is permitted to be carried downward below the table. It also has a claw 65 or aggressive toothed slat at its upper end. Both boards are provided with the usual aggressive slats a⁸ along their length to aid in positively carrying the grain down.

To the adjoining edges of the adjuster- 75 boards are attached plates a⁹ and a¹⁰, extending toward the front of the machine, the purpose of which is to prevent straws from getting between the boards as they move in their orbital paths.

80 It is found in practice that the action of my upper board upon the upper portion of the mass of grain confined between the deck and grain-cover tends to move the portion that lies below. For instance, if the board A³ alone were used the whole mass of grain would be moved in the direction of the binding-receptacle proper, the action of the board A³ would carry all straws with which it came in contact, and the agitation and forward movement of those would so influence all the straws beneath as to cause them to move down the table. In other words, the mass of straws being free to move and partially influenced by gravity, movement of the 85 upper stratum would carry the lower stratum therewith to a very great extent. The converse is true—that if the lower one of the two boards only were used the straws with which it came in contact would be moved deliveryward and the straws above would also be influenced to move in the same direction.

The coöperation of the two boards is such as to not only move the straws endwise for adjusting them so as to be centrally bound, but to in effect have two feeding-strokes downward to every revolution of the crank-shaft carrying them. This double action is found in practice to be a very material benefit.

I am aware that butt-adjusters have been made consisting of a series of toothed bars moved by cranks and adapted to be thrust through slots in the frame guiding them, in which case there was no means for producing a beating effect upon the butts of the entire mass of grain in the receptacle; but only teeth that at various horizons, as it were, above the binder-table should dig into the mass, and thus feed it by clawing actions. While this clawing action tends to work the grain down, it does not do so in a satisfactory manner.

One important function performed by my device is not found in the single-board adjuster. In the conditions of grain found in the early harvest the packers force the straw downward; but as they withdraw the latter springs back until the succeeding packer brings down its wisp, and, furthermore, the successive strokes of the packers, compacting the straw at the middle of the gavel, produce a tendency of the butts of the straws to recoil under the action of the butt-adjuster. With my device this recoil is very nearly prevented by the alternate strokes of the two parts, one acting upon the butt of the gavel while the other is making its return movement.

I claim—

1. The combination with the elevators the binding-table and the grain-cover, of a grain-adjusting device consisting of a plurality of orbitally-moved boards arranged one above the other and adapted to move in close relation to each other and also adapted to act alternately, and thus engage the butts of the straws in the receptacle, move them endwise and advance them deliveryward, each of said boards having a plate attached to the edge adjoining its fellow board, substantially as described.
2. The combination with the elevators, the binding-table, and the grain-cover, of a grain-adjusting device consisting wholly of two orbitally-moving boards placed edgewise in close proximity to each other, the plane of said boards being substantially perpendicular to the binding-table, and said boards being

operated so as to act alternately upon the butts of the straw upon the table, to simultaneously move the same endwise and side-
wise, whereby only one portion of the adjuster 60 is active upon the grain at a time, the other portion being meanwhile out of action, substantially as described.

3. The combination with the elevating-conveyors, the binding-table, and the grain-cover, 65 of a grain-adjusting device consisting wholly of orbitally-moving boards placed edgewise in close proximity to one another, the plane of said boards being substantially perpendicular to the binder-table, and said boards being operated so that, although the entire face of the adjuster is constantly in motion, the individual boards of which it is composed act alternately upon the butts of the straw upon the table to simultaneously move the same 75 endwise and sidewise, substantially as described.

4. In a grain-binding harvester, the combination with the receiving-table, the grain-cover, and the upper and lower elevating-conveyors, of a grain-adjusting device composed wholly of a plurality of orbitally-moving boards, one placed immediately above the other, the lower board located and adapted to sweep in close contact with the table, and the upper board located and adapted to sweep across the plane of the lower conveyer toward and near the end of the upper conveyer in close contact with the cover, and the two boards thus coöperating to clear the space between the roller of the upper conveyer and the overhead cover and between the roller of the lower conveyer and the edge of the receiving-table, substantially as described.

5. In a grain-binding harvester the combination with the binder receiving-table, grain-cover and upper and lower elevating-conveyors, of a grain-adjusting device composed of two orbitally-moving boards, one above the other, the lower one adapted to clear the space 95 between the grain-receiving table and the lower conveyer-roller, and the upper one to keep clear the space between the upper elevator-roller and the grain-cover, and plates attached to the adjoining edges of said boards 100 and projecting outwardly and adapted to prevent straws from getting between said boards, 105 substantially as described.

WILLIAM BUTTERFIELD.
